OILING DEVICE

Robert L. Harter, Hinsdale, Ill.

Application December 19, 1934, Serial No. 758,206

4 Claims. (Cl. 184—103)

My invention relates to an oiling device and more particularly to a temperature responsive oiler.

It is a well known fact that a large percentage of the oil ordinarily applied to bearings is wasted due to the lack of regulating means for supplying oil at the time and in the quantity required.

An object of the invention is to provide a new and improved oiling device.

10 Another object is to provide an oiling device which is automatic and effective in operation.

A still further object is to provide an oiling device which is uniformly and consistently responsive to temperature changes.

15 Other objects and advantages will appear as the description proceeds.

In accordance with one embodiment of the invention a chamber of thermally conductive material associated with a bearing is provided with 20 means for maintaining a constant ratio of air and oil whereby a predetermined temperature change in the bearing will produce a corresponding expansion of air in the chamber to expel a quantity of oil in accordance with the temperature change.

25 A complete understanding of the invention may be had by reference to the following description taken in conjunction with the accompanying drawing in which the single figure is a side view partly in section of an oiling device embodying the invention.

30 Referring now more in detail to the drawing a bearing 6 which may have a suitable lining or bushing 7 is shown provided with a threaded aperture for receiving a threaded stem 8 of the oiling device. The oiling device comprises a chamber 9 of a thermally conducting metal such as brass which is preferably integral with the stem 8. The stem is provided with a large bore 11 connecting with the chamber through a small aperture 12 of such a size that oil will not flow 35 therethrough when the device is assembled except when pressure is exerted on the oil.

The upper portion of chamber 9 has a threaded opening adapted to receive a cap 13 having an externally threaded portion 14 serving as a closure for the chamber and an internally threaded portion 15 serving as a closure for an oil supply reservoir 16. Suitable washers are preferably provided on the cap to make air-tight connections 40 with the oil chamber and the reservoir.

45 The cap 13 is provided with two downwardly extending tubes 17 and 18, one of which extends below the normal oil level in chamber 9. The tube 17 serves to allow the oil from the reservoir 50 to pass downwardly into chamber 9 and the tube

18 allows air from chamber 9 to pass upwardly into the reservoir until the level of the oil in the chamber rises to shut off the air to the end of tube 18 at which time the downward passage of oil in tube 17 is interrupted. The tube 18 is slightly bevelled at its lower end because it has been found that if the end of the tube is not bevelled the capillarity of the tube allows the oil to drop considerably below the end of the tube before the entrance to the tube is separated from the supply of oil in the chamber to allow the air to enter the tube. A more constant level of oil is therefore maintained.

5 In cases where a heavy oil is used a single tube of larger dimensions may be used in which the air may travel upwardly at the same time that the oil flows downwardly.

15 Due to the fact that the motion of the shaft in the bearing may cause a rarefaction or compression of air or a pumping action which in some cases interferes with the proper operation of the device, it is preferable to provide a vent 10 in the stem 8 to obviate the effect of this action on the 20 operation of the oiling device.

25 The operation of the device is as follows. When the shaft in the bearing begins to rotate the bearing temperature slowly rises, communicating its heat to the walls of the stem 8 and to the chamber 9. This causes the air in the chamber to expand and exert a pressure on the 30 oil to expel oil through the small aperture 12 onto the bearing. A cooling of the bearing causes the air in the chamber to contract and draw air into the chamber through the aperture 12. It appears that during the operation of the bearing 35 there is a slight drop in temperature when oil is supplied, followed by a rise in temperature when the oil becomes depleted. Thus there is provided an intermittent supply of oil as oil is needed. The air drawn into the chamber will, of course, 40 be transmitted to the reservoir and thus the ratio of oil to air in the chamber will remain constant so that a given change in temperature will always result in a definite amount of oil being supplied to the bearing. The reservoir is preferably made 45 of a relatively poor heat conducting material such as glass so that the air therein will be substantially unaffected by bearing temperatures.

50 In some cases where bearings are used which require very little oil, the chamber of the oiling device may be mounted out of heat conducting relationship with the bearing and the normal variations in room temperature will suffice to expel oil at sufficiently frequent intervals to keep the bearing lubricated. In such event the oiling 55

device may for example be connected to the bearing by means of a long tube.

It will be understood that the nature and embodiment of the invention herein described is merely illustrative and that many changes and modifications may be made therein without departing from the spirit and scope of the invention.

What I claim as new and desire to secure by 10 United States Letters Patent is as follows:—

1. A lubricating device comprising a lubricant feeding chamber having means connected to its lower end for supplying lubricant to a member to be lubricated, said chamber being made of a heat 15 conducting material, and means for maintaining a constant volume of air in said chamber, whereby the temperature changes of said air cause lubricant to flow from said chamber.
2. A lubricating device comprising a lubricant 20 feeding chamber having an aperture in its lower end for supplying lubricant to a member to be lubricated, means for connecting said aperture to the member to be lubricated, said means being of heat conducting material, and means for maintaining a constant volume of air over the lubricant 25 in said chamber whereby temperature

changes of said air cause lubricant to flow from said chamber.

3. A lubricating device comprising a lubricant feeding chamber having an aperture in its lower end for supplying lubricant to a member to be lubricated, a lubricant supply receptacle above said lubricant feeding chamber, and means for connecting said lubricant supply receptacle to said lubricant feeding chamber to maintain a predetermined volume of air in said lubricant feeding 10 chamber, whereby temperature changes of said air cause lubricant to flow from said feeding chamber.

4. A lubricating device comprising a lubricant feeding chamber having an aperture in its lower 15 end for feeding lubricant to a member to be lubricated, a lubricant supply receptacle, and a tube extending from the supply receptacle a predetermined distance into the lubricant feeding chamber to supply lubricant to the feeding chamber and maintain a fixed volume of air in the chamber whereby temperature changes of said air cause lubricant to flow from said feeding chamber.

ROBERT L. HARTER. 25
